UNITED STATES PATENT OFFICE.

FRANK L. HUTCHINSON, OF WAUWATOSA, WISCONSIN, ASSIGNOR, BY MESNE ASSIGNMENTS, TO MILWAUKEE VALVE COMPANY, OF MILWAUKEE, WISCONSIN, A CORPORATION OF WISCONSIN.

STEAM TRAP.

Application filed May 31, 1924. Serial No. 716,980.

To all whom it may concern:

Be it known that I, FRANK L. HUTCHINSON, a citizen of the United States, and resident of Wauwatosa, in the county of Milwaukee and State of Wisconsin, have invented new and useful Improvements in Steam Traps, of which the following is a description, reference being had to the accompanying drawings, which are a part of this specification.

This invention relates to improvements in steam traps, and more particularly to a steam trap adapted to be connected to the return pipe in a high pressure vapor or steam heating system.

In heating systems employed in buildings, where steam under pressure is employed, it is customary to control the admission of steam to the radiator and to provide an outlet pipe to return water of condensation back to the boiler. In order to make the system conducive of the best results and to provide for its maximum efficiency, it is necessary to prevent the passage of any of the live steam back through the return pipe with the water of condensation. It is also necessary in systems of this character to provide means whereby air which may be trapped in the radiator can escape, so that the air will not act to prevent the entrance of steam into the radiator.

With the above in mind, therefore, it is one of the objects of the present invention to provide a device adapted to be connected to the return pipe and constructed to permit the passage of water of condensation therethrough and also any air trapped in a radiator, but at the same time preventing the escape of live steam.

A further object of the invention is to provide a device of the class described particularly adapted for high pressure vapor and steam heating systems and arranged so that the valve is controlled by a compound leverage thereby obviating any sticking of the valve and insuring an efficient device.

A further object of the invention is to provide a steam trap which is of very simple construction, is strong and durable, and is well adapted for the purpose described.

With the above and other objects in view, the invention consists of the improved steam

trap and its parts and combinations as set forth in the claims, and all equivalents thereof.

In the accompanying drawing in which the same reference characters indicate the same parts in all of the views:

Fig. 1 is a front view of the improved steam trap, parts being broken away and shown in section;

Fig. 2 is an enlarged detail view showing the valve stem, the compound leverage for moving the same and the thermostatically controlled valve;

Fig. 3 is an enlarged detail view of the thermostatically controlled valve.

Referring now more particularly to the drawing it will be seen that the steam trap consists of a casing 8, provided with an inlet opening 9 and an outlet opening 10. The casing is formed immediately adjacent the inlet opening with a chamber 11 in which is seated a screen or basket 12 formed with perforated walls. Said member 12 serves to screen the water of condensation entering the casing through the opening 9 and collects sediment. The chamber 11 is provided with a cleaning opening 13 closed by a threaded plug 14 and when desired said plug can be removed and the basket 12 grasped by its handle 15 and lifted from the chamber to permit emptying and cleaning of the basket. An opening 16 formed in the wall of the chamber 11 provides communication between said chamber and the float chamber 17 of the steam trap. The upper side of the casing is open but is normally closed by means of a cover 18 removably held in place by bolt and nut means 19 and 20, a washer member or gasket 21 being interposed between the cover and the casing to prevent leakage.

Threaded in the bottom of the casing is a bushing 22 having formed therein a valve seat, adapted to receive a valve 23 carried by a hollow tubular valve stem 24. The valve 23 and stem 24 are mounted for reciprocal movement in a guide member 25 supported on a pair of projections 26 extending inwardly from the casing 8. The guide member 25 is formed with a central aperture for the reception of the valve stem 24.

Fixed to the valve stem 24 is a collar 27

which has pivoted to opposite sides thereof, the end portions of a pair of bell-crank levers 28. The mid-portions of said bell-crank levers are pivoted to a depending arm 29, formed from the guide member 25. A second pair of bell-crank levers 30 are pivoted at their outer end portions to said depending arm 29, as at 31, and at their mid portions to the lower end portions of the 10 first mentioned bell-crank levers 28, as at 32. A hollow float 33 is carried by the other ends of said bell-crank levers 30. Obviously, therefore, as the float is raised, the valve stem 24 and the valve 23 will consequently 15 be moved upwardly to unseat the valve. The compound leverage provided by the arrangement just described renders the operation of the valve positive under all conditions. A considerable movement of the 20 float results in but a small movement of the valve stem but the leverage arrangement results in great force being applied to the stem in raising or lowering the same. Consequently, any tendency the valve may have to stick, will be easily overcome. Thus, the 25 device is well suited for high pressure systems where pressure might cause the valve to become inoperative.

Fixed to the upper end of the tubular valve stem 24 is a collar 34 having secured thereto one end portion of a U-shaped, bimetal thermostat 35, formed preferably of an outer strip of brass or copper and an inner strip of steel or other similar metal, having a different co-efficient of expansion. The collar 34 has an angularly shaped bore 36 communicating with the valve stem opening and a valve 37, carried by the end of the thermostat 35 is adapted in its closed position to cover the open end of the bore 36, thus closing communication through the hollow valve stem between the chamber 17 and the outlet 10.

It should be observed that the casing 8 is 45 formed with a lower jacket portion 38 providing an outlet chamber 39. The valve opening in the bushing 22 opens thereinto and fluid is free to flow from said outlet chamber through the outlet opening 10. In 50 the wall of the casing adjacent the bushing 22 a similar bushing 40 is located, the same being formed with a valve seat to receive a valve 41. Said valve 41 is moved inwardly and outwardly by means of a hand wheel 42 55 and serves as an auxiliary valve so that water may be drained from the chamber 17 when desired, independently of the operation of the valve 23.

In operation the valve 23 will normally remain 60 in closed position, as shown in Fig. 1, while the thermostatic valve 37 remains in open position. Consequently any air flowing into the chamber 17, through the inlet opening 9, is free to pass from the chamber 17 through the tubular valve stem 24 and

downwardly through the chamber 39 and the outlet opening 10. As soon as any steam enters the chamber 17 the heat thereof will cause an unequal expansion of the bi-metal parts of the thermostat 35 and thus cause 70 the valve 37 to seat against the open end of the bore 36 to close the same and the live steam will be confined within the radiator.

The water of condensation which flows 75 into the chamber 17 will gradually accumulate until it reaches a height sufficient to actuate the float 33, which as it rises, will move the valve stem 24 and the valve 23 upwardly to permit an escape of the water into the chamber 39 and out through the outlet opening 10. As the level of the water decreases, the float will again drop and move the valve 23 to the closed position. When a sufficient 80 quantity of water has again accumulated in the chamber 17, the cycle will be repeated. 85

Obviously, as the water of condensation passes into the chamber 11, any foreign matter contained therein will be caught by and held in the basket member 12, which can be periodically removed through the opening 13 and cleaned out. Access into the interior of the steam trap and chamber 17 may be conveniently had by removing the cover 18, and should it become necessary to replace any portion of the operating parts illustrated in Figs. 2 and 3, this may be accomplished by detaching the guide member 25 from the projections 26, whereupon all of these parts may be removed as a unit from the interior of the valve. This facilitates, 90 to a considerable degree, the repairing or replacing of parts.

It is evident that the compound leverage arrangement between the valve and the float is constructed to exert great power in lifting the valve, thereby overcoming any tendency the valve may have to stick and also pressure thereon, making the device well suited for high pressure systems. Also the improved steam trap is of very simple and 105 novel construction; and is well adapted for the purpose set forth.

What I claim as my invention is:

1. A steam trap, comprising a casing 110 forming a chamber provided with inlet and outlet openings, a float, a valve provided with a valve stem for controlling said outlet opening, the stem of said valve having a passage providing communication between said chamber and outlet opening, means for closing said passage, and a compound leverage between said float and the valve stem for operating the valve.

2. A steam trap, comprising a casing 115 forming a chamber provided with inlet and outlet openings, a float, a valve provided with a valve stem for controlling said outlet opening, the stem of said valve having a passage providing communication between said chamber and outlet opening, a U-shaped 120

thermal member for closing said passage, and a compound leverage between said float and the valve stem for operating the valve.

3. A steam trap, comprising a casing forming a chamber provided with inlet and outlet openings, a float, a valve provided with a valve stem for controlling said outlet opening, the stem of said valve having a passage providing communication between said chamber and outlet opening, heat controlled means for closing said passage, and a compound leverage between said float and the valve stem for operating the valve.
10. 4. A steam trap, comprising a float cham-

ber provided with inlet and outlet openings, 15 a float, a valve for controlling said outlet opening, said valve being formed with a hollow stem providing a passage between said chamber and outlet opening, a thermostatically actuated valve mounted on the end of 20 said stem for controlling said passage, and a compound leverage between said float and the valve stem for operating said first mentioned valve.

In testimony whereof, I affix my signature.

FRANK L. HUTCHINSON.
